CLAIM

An ornamental design for a gaming table, as shown and described.

DESCRIPTION

FIG. 1 is a perspective view of my new design, a gaming table, in an open configuration;

FIG. 2 is a top view of the design of FIG. 1;

FIG. 3 is a bottom view of the design of FIG. 1;

FIG. 4 is a front view of the design of FIG. 1;

FIG. 5 is a back view of the design of FIG. 1;

FIG. 6 is a right side view of the design of FIG. 1;

FIG. 7 is a left side view of the design of FIG. 1;

FIG. 8 is a perspective view of the gaming table shown in a closed configuration;

FIG. 9 is a right view of the design of FIG. 8;

FIG. 10 is a left view of the design of FIG. 8;

FIG. 11 is a top view of the design of FIG. 8;

FIG. 12 is a bottom view of the design of FIG. 8;

FIG. 13 is a right side view of the design of FIG. 8; and,

FIG. 14 is a left side view of the design of FIG. 8.

The broken line showing is included for the purpose of illustrating portions of the "article" and forms no part of the claimed design.

1 Claim, 10 Drawing Sheets
